SMOKING TUBE

Edmund Bruder, Chicago, Ill.

Application June 3, 1936, Serial No. 83,239

11 Claims. (Cl. 131—22)

This invention relates to improvements in smoking tubes of the type shown and described in my application, Serial Number 20,653, filed May 9, 1935, and one of the objects of the invention is to improve in certain respects, the structure and arrangement of the parts shown therein, and to provide improved means for preventing moisture or saliva from contacting the tobacco, and to provide means within the smoking tube for 10 catching and confining the saliva.

A further object is to provide an improved device of this character in which the tobacco may be inserted in a loose condition or in the form of a cigarette or cartridge, and improved means 15 for automatically advancing the tobacco to the lighted end of the device as the tobacco is consumed.

A further object is to provide an improved device of this character which is of a sectional construction, comprising parts detachably secured together, whereby the insertion of the smoking material may be readily accomplished, and whereby the parts of the device may be readily separated to facilitate cleaning thereof.

To the attainment of these ends and the accomplishment of other new and useful objects as will appear, the invention consists in the features of novelty in substantially the construction, combination and arrangement of the several parts hereinafter more fully described and claimed and shown in the accompanying drawings illustrating this invention, and in which

Figure 1 is a longitudinal, sectional view of an improved device of this character constructed in accordance with the principles of this invention.

Figure 2 is a detail sectional view of the cap member of the device.

Figure 3 is a detail sectional view of the end member.

Figure 4 is a detail sectional view of a rotatable abutment member for the tobacco.

Figure 5 is a detail view, partly in elevation and partly in section, of the body member having 45 associated therewith a plunger.

Figure 6 is a detail sectional view of the stem member or mouth piece.

Figure 7 is an assembled detail sectional view 50 of a portion of the device, on an enlarged scale.

Figure 8 is a top plan view of Figure 2.

Figure 9 is a top plan view of Figure 4.

Figure 10 is a top plan view of Figure 3.

Figure 11 is a top plan view of Figure 5, taken 55 on line 11—11, Figure 5.

Figure 12 is a detail sectional view taken on line 12—12, Figure 5.

Figure 13 is a detail sectional view taken on line 13—13, Figure 6.

Figure 14 is a detail perspective view of one

form of retaining spring for rotatably securing the cap and end members together.

Figure 15 is a perspective view of another form of retaining member.

Figure 16 is a detail sectional view on line 16—16, Figure 7.

Figure 17 is a detailed elevation of a portion of the end member.

Referring more particularly to the drawings, the numeral 20 designates generally a body portion or member, which may be constructed of any suitable material and of any desired size and configuration. The ends of the body are recessed at 21—22 to form a dividing partition 23 having a central opening therethrough, and projecting axially from one end of the body member is a tubular member 24 of any desired length and diameter and which is provided with a closed bottom 25. The tubular member 24 may be formed integral with the partition 23 or may be formed separately and attached thereto, and has communication with the central opening through the partition 23. This opening is preferably of a diameter somewhat larger than the diameter of the tubular member 24 and the wall of the opening is provided with a threaded recess 26, for a purpose to be later described.

The recess 21 is provided with screw threads 27, while the wall of the recess 22 is preferably smooth.

The partition 23 may be provided on one face with a groove 28 communicating with the recess 22, and openings 29, any number of which may be provided, extend through the bottom of the groove 28 to form communications between the groove 28 and the recess 21.

The numeral 30 designates a hollow end member which is provided with a body portion having a reduced end 31 having external screw threads 32. The other end of the member 30 is closed as at 34 and has a central opening 35 therethrough, and openings 36 are provided in the end 34 to encompass the opening 35. The end member 30 may be of any desired and suitable length.

Extending across the openings 36 and projecting respectively beyond the opposite faces of the end wall 34 are scrapers 37—38, and these scrapers are of a thickness considerably less than the diameter of the openings 36 so as not to obstruct the openings to any great extent.

The end member 30 is attached to the body member 20 by causing the threads 32 thereon to engage the threads 21 in the wall of the recess 21, and when assembled, a shoulder 39 formed by the reduced end 31 of the member 30 will abut the end of the body portion 20. The external contour of the member 30 is shaped to conform to the contour of the body 20, and if desired portions of the end member 30 may be removed as at 40, 50 55 60 65 70 75 80 85 90 95

for the sake of ornamentation and also for the purpose of imparting lightness to the structure.

The numeral 41 designates a stem or mouth piece which may be of any desired size and configuration and is provided with a reduced extremity 42 having a smooth periphery providing a shoulder 43. This extremity 42 is adapted to fit in the smooth recess 22 of the body member 20 so that the two will be frictionally bound together 10 and so that the shoulder 43 will abut the end of the body member 20.

Within the stem 41 are passages 44, any number of which may be provided. One end of each passage opens through the extremity 45 of the stem and the other end of each passage has communication with a chamber 46 in the stem. A portion of the stem within the chamber 46 projects above the bottom of the chamber and is of an external diameter considerably less than the 20 internal diameter of the chamber so as to form a pocket 48 to prevent saliva from running back through the openings or passages 44.

The portion 47 terminates short of the top of the chamber and a closure 49 is provided for the 25 chamber. This closure is provided with a reduced portion 50 forming a shoulder 51 and a tubular extension 52 which is of a diameter considerably less than the diameter of the closure. The reduced portion enters the chamber 46 and the 30 closure is frictionally held in position with the shoulder 51 abutting the end of the stem or mouth piece 41. The periphery of the closure 49 is preferably beveled or shaped as at 53 to form a finger engaging portion to facilitate the removal of the 35 closure when desired, and a recess or pocket 54 is provided which opens through the top of the closure and communicates with an opening 55 which extends through the portion 52 of the closure.

40 The reduced end 42 of the stem 41 is of such a length that when the shoulder 43 abuts the inner end of the body member 20, the inner extremity of the stem member will terminate short of the partition 23 in the body member 20 to form a 45 recess or chamber in which is arranged a filter 56, constructed of any suitable material and preferably in the form of a disc, which substantially fills the space between the extremity of the stem member 41 and the proximate face 50 of the partition 23 of the body member 20. This filter will extend over the groove 28 in the partition 23, as well as over the recess 54 in the closure member 50 at the end of the stem or mouth piece 41.

55 Within the tubular member 24 is arranged a plunger 57 to which is connected a stem 58, and to the end of the stem is connected a head 59 having any desired number of openings 60 therethrough, and the head 59 is of a diameter to substantially fill the chamber 61 in the end member 30. The periphery of the head 59 is preferably beveled as at 62 to form a substantially sharp edge 63 which contacts and moves along the wall of the chamber 61 in the end member 30. A nut 64 encompasses the rod or stem 58 and is adapted to be threaded into and seated within the recess 26 in the partition 23 so as to form a guide for the stem 58 and to hold the same centrally positioned.

70 Recesses 65 are provided in the upper face of the nut 64 by means of which the nut 64 may be readily removed or seated when desired, and in a manner to be set forth.

The head 59 is preferably provided with a hub 75 66 and pins 67 project below the end of the hub

and are adapted to be seated within the recesses 65 in the nut 64 and to be removed therefrom. When seated in the recesses, it will be manifest that by placing the finger upon the head 59, when the end member 30 is removed, and rotating the head in the proper direction, the nut 64 may be screwed out of its seat. Likewise, by depressing the head 59 and rotating the same in the opposite direction, the nut 64 will be seated.

A spring 68 is provided in the tubular member 10 24 between the closed end 25 thereof and the lower end of the plunger 57, and the normal tendency of the spring 68 is to advance the plunger 57 to move the head 59 toward the closed end 34 of the chamber 61 in the end member 30, for a 15 purpose to be described.

The advancing movement of the head 59 and plunger 57 under the stress of the spring 68 will be arrested by reason of the end of the plunger 57 contacting with the lower face of the nut 20 64.

The numeral 69 designates an abutment member which is provided with a stem 70 angular in cross section, preferably having two opposed flat sides, although the stem may be of any desired 25 configuration in cross section. The stem 70 is formed by reducing a portion of opposite sides thereof to provide a shoulder 71 and a circumferential groove 72 is provided in the stem.

This abutment member is placed in position 30 30 within the chamber 61 in the end member 30 through the open end thereof, so that the stem will pass through the opening 35 to such an extent that the groove 72 will be disposed beyond the outer surface of the end wall 34 of the chamber 35 61 of the end member 30, but in proximity thereto.

Openings 73 pass through the member 69, and any number may be provided and may be suitably arranged so that they may be moved into 40 and out of alignment with the openings 36 in the end wall 34 of the end member 30. In the upper face of the member 69 is an annular groove 74 with which the openings 73 communicate.

The numeral 75 designates a cap member which 45 is hollow and is provided with a partition 76 intermediate the ends of the member. The portion of the cap below the partition 76 forms a recess or chamber 77 having a circumferential groove 78 in the inner wall thereof and spaced 50 from the ends of the chamber. Also provided in the wall of the chamber 77 are any desired number of grooves 79 (see Figure 2) which intersect the groove 78 so as to form spaces for the reception of locking elements to be hereinafter described. The portion of the member 75 above the partition 76 forms a chamber 80, and the outer wall of this chamber may be cut away or recessed as at 81, for the purposes of ornamentation and also for the purposes of imparting lightness to the structure.

A projection 82 extends beyond the partition 76 into the chamber 80 and is preferably centrally located. This projection is hollow and communicates with the chamber 77 through the 65 partition 76. One part of the hollow portion of the projection 82, such as at 83 (see Figure 2), is of a diameter considerably greater than the diameter of the portion 84 to form a shoulder 85 against which the shoulder 71 of the stem of 70 70 the abutment member 69 rests, while the portion 84 in the projection 82 is angular in cross section to conform to the contour of and receive the angular portion 70 of the abutment member 69.

Openings 86 extend through the partition 76 to form communication between the chamber 80 and the recess or chamber 77, and any desired number of these openings may be provided.

5 A groove 87 is provided in the lower face of the partition 76, and with which groove the openings 86 have communication.

When the abutment member 69 is placed in position in the cap member 75 with the recess 72 above or beyond the wall of the end member 30, but in close proximity thereto, a fastening device, such as a C shaped spring 88 is placed within the recess 72 so as to extend beyond the wall of the opening 35 and rests against the 10 outer face of the wall 34 at the end of the end member 30. This will secure the abutment member 69 to the cap member 75 so that both will be rotatable with respect to the end member 30. When thus assembled, the end wall 34 of the 15 end member 30 will be disposed between the abutment 69 and the partition 76 in the cap member 75. The outer face of the end wall 34 will abut the lower face of the partition 76, and the upper face of the abutment 69 will contact 20 the inner face of the end wall 34.

Owing to the angularity of the portion 70 of the abutment 69 and the angularity of the recess 84 in the cap member 75, these two elements will be secured for simultaneous rotation with 25 respect to the end wall 34 of the end member 30.

In this position the grooves 74 in the abutment member 69 will be in communication with the openings 36 through the end wall 34 of the member 30, when the parts assume a predetermined relative position so as to bring the openings 86, grooves 87, openings 36 in the end member 30, grooves or recesses 74 in the abutment member 69, and the openings 73 through said abutment member, in registration. However, 30 when the cap member 75 is rotated with respect to the end member 30 the openings 86 in the cap member and the openings 73 in the abutment member will be moved out of registration with the openings 36 in the end wall 34 of the end member 30.

The cap member 75 is placed in position by inserting the end of the end member 30 into the chamber 77 in the cap member until the end 35 of the cap member abuts the peripheral shoulder 91 on the end member 30.

These parts when thus assembled are detachably secured together but for relative rotary movement, preferably by means of a semi-circular member 92 constructed of any suitable material and provided with depending parallel arms or portions 93 at the ends thereof.

The portion 92 of this member is adapted to be seated in a recess 94 (see particularly Figure 17) in the periphery of the end member 30, while 40 the arms or portions 93 are adapted to be seated in slots 95 which are arranged at right angles to and communicate with the groove or recess 94. Portions of the walls of the slots 95 are recessed as at 96 to form a cavity 97 and the bottom of the 45 slots 95 is preferably concaved, as at 98.

The numeral 99 designates globular members, through which the arms or portions 93 of the member 92 loosely pass.

When the portion 92 is seated in the groove 70 94 and the portions 93 seated in the slots 95, the globular members 99 will be seated in the cavities 96. These members 99 are of a diameter that in the normal position of the portions 93 of the member 92, they will project for a suitable distance beyond the periphery of the end member

5 30, so that when the cap member 75 is placed upon the end of the end member 30, the inherent resiliency of the member 92—93 will cause portions of the globular members 99 to be seated in the recess or groove 78 in the wall of the chamber 77 of the cap member 75.

By reason of the concaved bottoms 98 of the slots 95, it will be manifest that while the cap member 75 is being placed upon the end member 30, the portions 93 of the member 92 will be 10 flexed by reason of the globular members 99 contacting the wall of the chamber or recess 75, to permit such assembling, and as soon as the cap member is seated upon the end member 30, and the groove 78 properly positioned with respect to the globular members 99, the latter will, through the resiliency of the elements 93 be forced into the groove 78 so that the cap member will be rotatably secured to the end member. 15

The resiliency of the members 93, however, is 20 such that the parts will under normal conditions be locked together, but, under abnormal force the cap member may be removed from the end member 30 by moving or forming the same lengthwise and away from the end member 30. The 25 recessed portions 96 of the walls of the slot 95 forming the cavities 97 also serve the purpose of preventing the globular members 99 from dropping out of position with respect to the members 93. 30

The intersections 79 (see Figure 2) of the groove 78 form seats or interruptions in the grooves 78 into which the globular members 99 are forced when the cap member has assumed a predetermined rotated position with respect to 35 the end member 30 to lock the parts in this adjusted position.

When it is desired to light the contents of the chamber 61, the cap member 75 with the abutment member 69 are rotated with respect to the 40 end wall 34 of the chamber 61 of the end member 30 so as to bring all of the openings in direct alinement, thereby enabling the contents of the chamber 61 to be ignited.

After the ignition, the cap member 75 may be 45 rotated in the manner just described, so as to move the openings 86 and the openings 73 through the end member 70 out of direct register or alinement with the openings 36 in the end wall 34 of the end member 30, so that the air entering the 50 combustion chamber 61 will flow through a tortuous passage. That is, through the openings 86 and grooves 87, thence through the openings 36 in the end wall 34 of the end member 30 and then through the openings in the abutment member. 55

In Figure 15 is shown another form of locking means for securing the cap member 75 rotatably to the end member 30, and in this modified form, the numeral 100 designates a C shaped body portion having arms or depending portions 101, portions 102 of which latter are deflected to form projections to enter the groove 78 in lieu of the globular members 99. 60

The stem member 41 is provided with a recess 65 103 (see Figure 6) intermediate the grooves or passages 44, and a portion of the stem which passes through the chamber 46 is of an external diameter considerably less than the diameter of the chamber 46 to form a tubular portion 104, 70 the extremity 105 of the tubular portion projecting above the end of the portion 42 of the stem member, so that when the closure 49 for the chamber 46 is in position, the upper surface of the closure will be substantially flush with the 75

extremity 105 of the tubular portion 104, (see particularly Figure 6), so as to assist in supporting the filter 56 in position.

Either the entire opening 55 or portions thereof, through the projecting portion 52 of the cap member 49 is or may be of a diameter slightly greater than the external diameter of the portion of the tubular extension 104 which passes therethrough so as to provide a passageway 106 between the wall of the opening 55 and the periphery of the tubular extension 104, so that the air currents and the smoke which is drawn from the combustion chamber 61 through the openings 29 in the partition 23 of the body member, and through the filter 56 into the recess 54 in the cap member 49, will flow into the saliva collecting chamber 46 through the opening 106. From the chamber 46 the smoke will be drawn through the stem member by means of the passages 44.

Obviously, the passage 106 may be a single passage or may be a plurality of passages, as shown more clearly in Figure 13.

The scrapers 37 and 38 are provided for the purposes of respectively removing foreign matter from the grooves 87 and 74 respectively in the partition 76 of the cap member 75 and in one face of the abutment member 69.

Obviously, the grooves and passages in the various parts may be of any desired width, length and configuration.

The product 107 to be smoked may be either in the form of loose tobacco, cigarette or cartridge, and if in the form of a cigarette or cartridge, is of a diameter to substantially fill the chamber 61 in the end member 30. To insert the same, the end member 30 with the cap member 75 attached thereto is detached from the body member 23, and the cigarette, cartridge or tobacco is inserted into the chamber 61, after which the end member 30 is secured to the body member 23. When the product has been placed in the chamber 61 of the end member 30, the end member is secured to the body member and during such securing operation the end of the product, if a cigarette, or the end of the charge, will contact with the head 59, and the latter will be depressed against the stress of the spring 68.

Inasmuch as the openings in the abutment 69, the partition 76 in the cap member 75, and the openings 36 in the end wall 34 of the end member 30 are placed in alinement, it will be manifest that by applying a lighted match the tobacco will be ignited through the registering openings.

During the smoking operation, the smoke will be drawn through these openings in the head. If the openings are in direct registration, there will be a direct draft through the openings, but if the cap member is rotated so as to move these openings out of direct but into indirect communication, the passage of the air being drawn into the chamber 61 will be in a tortuous passage.

During the smoking operation the smoke will be drawn through the filter 56, thereby causing a filtration of the smoke and the removal of a considerable portion of the nicotine.

The saliva will accumulate in the saliva collecting chamber 46 and the saliva will be prevented from flowing through the passages 44 in the stem 41 by reason of the pocket formed by the projecting portions 47 extending into the chamber 46 and the filter 56 will prevent the saliva from running back into the combustion chamber to contact with the tobacco.

As the tobacco is consumed, the spring 68 will

cause the head 59 to force the unconsumed tobacco into contact with the abutment 69, and this operation will continue until the tobacco is consumed.

The advancing movement of the head 59 under the stress of the spring 68 will be interrupted by contact of the plunger 57 with the nut 64.

During the smoking operation, if it is desired to remove any ashes which may accumulate or form at the end of the tobacco adjacent the abutment member 69, the latter may be rotated by rotating the cap member 75 with respect to the end member 30, and this will cause the ashes to pass through the registering openings to be discharged through the chamber 80 in the cap member 75.

With this improved construction it will be manifest that a simple and practical device is provided, and a sanitary construction will result, it being possible to separate all of the parts if desired, for the purpose of cleaning, and if desired, the stem 41 may be removable in order to permit of the changing of the filter material 56.

While the preferred forms of the invention have been herein shown and described, it is to be understood that various changes may be made in the details of construction and in the combination and arrangement of the several parts within the scope of the claims, without departing from the spirit of this invention.

What is claimed as new is:—

1. A smoking tube embodying two sections, a portion of one section telescoping into the other, means for detachably securing said sections together and for rotation one with respect to the other, said means embodying a resilient element disposed between the surfaces of the sections, means supported by said element and adapted to be yieldingly seated in registering seats in the adjacent surfaces of said sections, and means whereby the last recited means may be moved to a position within the space bounded by the contacting surfaces by a separating movement of said sections.

2. A smoking tube embodying a hollow section one end of which is open, a wall at the other end of the section forming a closure therefor, an end section telescoping with the first said section, a wall in the end section abutting the said wall in the other section, there being openings in said walls adapted to be brought into and out of register by rotating one of said sections, an abutment in said hollow section adjacent said end wall, means forming a connection between said abutment and said end section for securing them together for simultaneous rotation, there being openings in the abutment adapted to be shifted with respect to the said aligned openings, and means for temporarily locking said sections against relative rotary movement.

3. A smoking tube embodying a hollow member constituting a tobacco chamber, an annular groove opening in the periphery of the member, vertical slots intersecting said annular groove, portions of the walls of the slots being enlarged to form seats, the bottoms of the slots being concaved, a substantially C shaped spring seated in the annular groove, the ends of the spring being shaped to be seated in said slots, enlargements on said ends disposed in said seats, to normally project beyond the periphery of said member, a member telescoping with the first said member, an annular groove in the inner wall of the last said member registering with the first said annular groove and adapted to receive said enlarge- 75.

ment on the ends of said spring member, and interruptions in the annular groove in the second said member to receive a portion of said enlargements to form a lock for temporarily locking said 5 members against relative rotation.

4. A smoking tube embodying a hollow member constituting a tobacco chamber, an annular groove opening through the periphery of the member, slots intersecting said groove, portions 10 of the walls of the slots being enlarged to form seats, a substantially C shaped spring seated in said groove, the end portions of the spring being seated in said slots, locking elements disposed in said seats and through which elements the end 15 portions of the spring respectively loosely pass, said elements being maintained in position upon the ends of the spring by said seats and normally projecting beyond the periphery of the said member to enter a groove in the inner face of the wall 20 of a member which telescopes with the first said member, and seats in the last said groove for receiving a portion of said elements for yieldingly locking said members against relative rotary movement.

25 5. A smoking tube of the character described comprising a body embodying separable and telescoping sections relatively rotatable, a tobacco chamber in one of the sections, means disposed between the adjacent faces of the telescoped sections 30 and entering recesses in said faces for yieldingly locking said sections against separation but permitting relative axial rotation, a portion of one of said recesses being shaped to permit the said means to be depressed below the periphery 35 of that section which contains the last recited recess, to permit assembling and disassembling of said sections with respect to each other.

6. A smoking tube of the character described embodying separable axially aligned sections, one 40 of said sections being hollow and provided with end walls to form a tobacco chamber, there being openings through said walls, a follower in the tobacco chamber, a stem on the follower, a bearing threaded into one of said walls and through 45 which bearing said stem freely slides, means tending normally to urge the follower forwardly in the tobacco chamber, means serving to limit the movement of the follower under stress of the last said means and means on said follower 50 and said bearing adapted to be brought into interengaging relation when the said sections are separated, whereby upon axial rotation of said follower the said bearing may be unscrewed from its seat.

55 7. A smoking tube of the character described embodying axially aligned sections telescoping one with the other, a circumferential channel in the periphery of one of said sections, grooves intersecting the said channel, the bottoms of said 60 grooves being concaved, the walls of the grooves having opposed recesses communicating with the respective grooves, a resilient member seated in said channel and provided with arms seated in said grooves, formations on said arms seated in 65 said recesses and normally projecting beyond the periphery of that section in which said grooves are located, and a channel in the inner face of the other member to receive the said formations to yieldingly lock the sections against separation 70 but for rotation one with respect to the other.

8. A smoking tube of the character described embodying axially aligned sections telescoping one with the other, a circumferential channel in the periphery of one of said sections, grooves intersecting the said channel, the bottoms of said 75

grooves being concaved, the walls of the grooves having opposed recesses communicating with the respective grooves, a resilient member seated in said channel and provided with arms seated in said grooves, formations on said arms seated in 5 said recesses and normally projecting beyond the periphery of that section in which said grooves are located, a channel in the inner face of the other member to receive the said formations to yieldingly lock the sections against separation 10 but for rotation one with respect to the other, and seats in the last recited channel for receiving said formations for yieldingly locking said sections against relative rotation.

9. A smoking tube of the character described 15 embodying a plurality of axially aligned sections separably secured together, a tobacco chamber in one section and having an end wall, an abutment in the tobacco chamber, means for urging the tobacco against the abutment, a stem on the abutment passing through an opening in said end wall, and a fastening element recessed in said stem and contacting the said wall for rotatably securing the abutment in position, a portion of said stem beyond said fastening means being angular in cross section, there being a recess in the other of said sections conforming in contour to and receiving the said angular portion 20 of the stem, whereby upon rotation of the said other section with respect to the first said section said abutment will also be rotated in said tobacco chamber.

10. A smoking tube of the character described 25 embodying a plurality of axially aligned sections separably secured together, a tobacco chamber in one section and having an end wall, an abutment in the tobacco chamber, means for urging the tobacco against the abutment, a stem on the abutment passing through an opening in 30 said end wall, and a fastening element recessed in said stem and contacting the said wall for rotatably securing the abutment in position, a portion of said stem beyond said fastening means being angular in cross section, there being a recess in the other of said sections conforming in 35 contour to and receiving the said angular portion of the stem, whereby upon rotation of the said other section with respect to the first said section said abutment will also be rotated in said tobacco chamber.

11. A smoking tube of the character described 40 embodying a plurality of axially aligned sections separably secured together, a tobacco chamber in one section and having an end wall, an abutment in the tobacco chamber, means for urging the tobacco against the abutment, a stem on the abutment passing through an opening in 45 said end wall, a fastening element recessed in said stem and contacting the said wall for rotatably securing the abutment in position, a portion of said stem beyond said fastening means being angular in cross section, there being a recess in the other of said sections conforming in contour to 50 and receiving the said angular portion of the stem, whereby upon rotation of the said other section with respect to the first said section said abutment will also be rotated in said tobacco chamber, said sections being adapted to be axially rotated one with respect to the other, and means for yieldingly locking said sections against 55

60 such relative axial rotation.
